UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

MANIFOLD-WEB-PRINTING MACHINE.

Application filed October 9, 1925. Serial No. 61,431.

This invention relates to manifold-web-printing machines, and also to methods of using the same, both in connection with typewriting machines and independently thereof.

5 A business firm, such as a bank, often sends its customers brief communications, usually typed on small standard forms, each of which bears data that is required to be copied on a plurality of associated forms for 10 the information and records of certain departments of the bank. To prepare rapidly and economically sets of such communications in large quantities, it is desirable to manifoldly print and type, as much as possible, the information appearing thereon, and to reduce to a minimum the operations required for inserting and removing the sets from the printing and typewriting machines.

In my co-pending application, Serial No. 20 631,956, filed April 14, 1923 (now Patent No. 1,592,470, dated July 13, 1926), is disclosed a method of preparing sets of communications by feeding a work-web, having superposed plies on which have been printed 25 blank forms, to a hand-operated addressing machine for manifolding addresses or other items on the forms, the work-web being subsequently fed to a fan-folding typewriting machine for manifoldly typing additional 30 data on the forms.

Work-webs sometimes have an extra large number of superposed plies to be manifolded, and in such cases, there is employed a power-driven addressing machine which can engage its platen against the web with a heavy pressure. Accordingly, in the present invention, a motor driven addressing machine which moves a roller platen rearwardly over a work-sheet is arranged with 35 rollers for guiding a work-web fan-folded longitudinally and transversely from a work-pile in the rear over the type plate magazine to the printing bed of the machine. A carbon-holder is positioned at the 40 rear of the printing position and holds carbon-sheets interleaved with the plies of the web in such a way that the rolling travel of the platen on the work-web will not tend to 45 tear the carbon-sheets from the holder.

50 For keeping the web aligned at right angles to the printing line, adjustable side gages are positioned at the front and rear of printing position. A feature of the invention is the employment of the transverse fold line for gaging the forms to printing

position by bringing the fold lines even with the pointer positioned ahead of printing position.

Another feature is the provision for manually feeding or pulling the web over the 60 printing bed in the opposite direction to the rolling travel of the platen whereby any tendency of the upper layers of the web to creep under action of the rolling platen can be conveniently and positively resisted by 65 the operative's hold on the web ahead of the platen.

The arrangement for hand-feeding of the transversely fan-folded web by an operative at the delivery end of the addressing machine also permits the operative to conveniently inspect the printing being done, and control the forming of the printed portion of the web into a neat, satisfactory work-pile with its leading end accessible. The 70 latter result permits the web to be conveniently fed to a fan-fold typewriting machine for typing additional data on the forms 75 prior to their distribution, as described in said application.

80 Other features and advantages will hereinafter appear.

In the accompanying drawings,

Figure 1 is a fragmentary side view, shown partly in section, of a roller-platen addressing machine having my invention applied thereto.

Figure 2 is a fragmentary sectional view of a carbon-sheet-holding mechanism of the present invention, arranged on the addressing 90 machine.

Figure 3 is a plan view of the frame of the addressing machine illustrating the carbon-sheet-holding mechanism and web side gages of the present invention.

Figure 4 is a fragmentary plan view of the addressing machine, showing the fan-folded web in printing position.

Figure 5 is a fragmentary, vertical, longitudinal, sectional view through the addressing machine looking towards its right-hand side.

Figure 6 is a fragmentary front end view of the addressing machine, showing the arrangement of the platen and the machine's 105 inking ribbon with respect to the carbon-sheet.

Figure 7 is a fragmentary view of the web unfolded, so as to lie flat.

A multiple addressing machine may in- 110

clude a main horizontal frame 10 having an upright magazine 11 arranged for holding a plurality of printing plates 12 of the kind commonly used in addressing machines. 5 Horizontal rollers 13 and 14 may be mounted at the top and a roller 15 may be mounted adjacent the rear and at the bottom of the plate magazine 11 for passing or guiding a work-web W, which has been longitudinally and transversely fan-folded, from a workpile W^a at the rear of the machine over the top of the magazine, downwardly to the under side of a roller 16 mounted on the frame 10 in front of the magazine. A carbon-holder mounting plate 17 is mounted a short distance ahead of the roller 16 and is provided with two blocks 18, one being positioned on each side of the web and arranged with step portions on which may be 10 mounted stiff, thin blades 19 for holding carbon-sheets 20 interleaved between the longitudinal plies A, B, C, etc., of the work-web W. The blades 19 may extend alternately from opposite sides between the longitudinal plies of the web. To permit new and unused portions of the carbon-sheets 20 to be easily moved forward while still between the plies of the web to printing position whenever desired, the carbon-holder 15 plate 17 may be slidably mounted on a base-plate 21 having two downwardly-projecting boss-members 22 arranged for engaging in a slot 23 in the main frame 10, said bosses being drilled to receive cap-screws 24 for fastening the plate to the frame. A pair of pins 25 may be riveted to the lower side of the plate 17 for removable engagement in sets of paired holes 28 in the base-plate 21. To hold the slideable carbon-holder plate 20 down against the base-plate, two flexible fingers 29, having finger-pieces 30, may be pivoted on the base-plate 21 and arranged to bear upon the carbon-holder plate with a light pressure.

40 45 50 55 60 65 70 75 80 85 90 95 100 105 110 115 120 125

For keeping the web W correctly aligned at right angles to the printing line when passing through the addressing machine, rear side gages 31 may be adjustably mounted on the blocks 18 by thumb-screws 32 and front side gages 33 in the form of short inwardly-extending fingers fastened on collars 34, which may be adjustably mounted by set-screws 34^a on a stiff rod 35 held in brackets 36 fast on the forward end of the addressing machine, the latter gages being on the opposite side of the printing position from the rear gages. A thin plate 40 having a rectangular printing opening 41 may be fastened on a printing bed portion 10^a of the frame 10 over an inked ribbon 42, which may be arranged with automatic means of any suitable kind for feeding it across the web. The plate 40 prevents the first ply of the web from being smudged by the ribbon.

65 70 75 80 85 90 95 100 105 110 115 120 125

A roller-platen 50 may be brought down against a set of forms F of the web W at printing position, and rolled rearwardly with a sufficient pressure to manifoldly print the several forms from the plate 12 which is at the printing bed 10^a at the time. The platen movement is effected by the operative pressing a foot treadle 44 to operate a clutch mechanism, not shown, which may be the same as is commonly used in punch presses, to cause the engagement of a rocking arm 60 with a shaft 61, the latter being fast to a pulley 62 driven by a belt 63 connected to a motor, not shown. A link-member 64 may connect the rotating arm 60 to a pivoted operating member 65 having a cam portion 65^a, the latter being arranged to cam a roller 66 mounted in the lower end of a platen-lever arm 67 fast on a pivot-shaft 67^a. Under the forward upper end of the platen arm 67 may be adjustably mounted a guide-plate 68, which will be substantially parallel with the bed of the main frame 10 when the arm 67 is swung to its down position. The platen 50 may be mounted on a shaft 50^a in the lower ends of two vertical cross-arm members 70 at the front of a platen-frame 71 that is pivotally connected at the rear to a lower arm 72 of a bell-crank lever 73 pivoted on a shaft 73^a mounted on the top of the platen-arm 67. Overhanging pins 74 in the upper ends of the cross-arm members 70 may loosely slide upon the upper face of the guide-plate 68. Rollers 75, mounted on a shaft 76 in said cross-arm members 70, may engage against the lower faces of the guide-plate 68 and also against rollers 77 on the platen-shaft 50^a for reducing friction when the platen is being rolled over one of the printing plates 12. A contractile spring 78, having one end secured to the frame 71 and the other to the platen-arm 67, may be arranged for yieldingly holding the rollers 75 in engagement against lower faces of the guide-plate 68. To prevent the upper end of the platen-arm 67 from being lowered too far, a stop rod 79, whose lower end engages against the frame 10, is threaded into a lug 80 on the side of the platen-arm 67, and is provided with an adjusting lock nut 81.

130

The following described mechanism for rolling the platen 50 rearwardly may be provided. An operating device 82 (see Figure 1), having laterally projecting lugs 83 and 84, may be loosely mounted on the shaft 67^a and be operatively connected, by means of a link-member 85, with the operating member 65. One end of an arm 87 arranged between lugs 83 and 84 may be loosely mounted on the shaft 67^a and have its other end connected by a pin 88 to the lower end of an upwardly extending link 89, whose upper end may be loosely connected with the upper arm 73^b of the lever 73. One end of a link 90 may also be loosely engaged about

the pin 88, and have its other end loosely connected with the upper end of an arm 91, whose lower end is loosely engaged about a pin 92 in the end of a rearwardly projecting portion of the platen-arm 67. The operating member 65 moves through a portion of its clockwise travel without affecting the arm 87. The device 82 will, however, swing until the lug 84 engages the arm 87, and moves the latter together with the link 89 upwardly. The arm 73^b will now be swung upwardly and the arm 72 rearwardly, the latter moving with it the platen 50 which has been swung down against the printing bed. The lug 83 upon return movement of the operating member 65 will engage the arm 87 to move it downwardly and thereby effect, through the above-described lever system, the return movement 20 of the platen 50 to a starting position. The arm 91 is engaged by a tensile spring 93 which tends to pull it clockwise, and cause it to act through links 89 and 90 and the lever 73, so as to hold the platen in its rear position until the platen-arm 57 has been raised. The positioning of the rearwardly moving platen in front of the carbon-sheets 20 prevents any used and weakened portions of the carbon-sheets from being subjected to 30 strain from the movement of the platen, and also guards against any creeping of the web under the moving platen from tearing the carbon-sheets 20 from the blades 19.

The printing-plates 12 may be pushed from the magazine 11 along on the upper surface of the frame 10 to printing position by spring-pressed dogs 95 mounted in a frame 96, arranged for sliding forwardly and rearwardly on rollers 97 on the main frame. An arm 100 fast on shaft 67^a rotates clockwise with the latter upon downward movement of the platen 50, and being connected by a link 101 to a short arm 102 of the lever 103, pivoted on a pin 104, swings the lever 103 counterclockwise, and the latter, being connected by a link 106 with the movable frame 96, pulls the latter with it rearwardly. The rearmost set of dogs 95 engages behind the lowermost plate 50 12 in the magazine 11, and, upon upward movement of the platen, moves the plate forward. Upon successive printing cycles of the platen, the plate is pushed in turn by the second and third sets of dogs to printing position on the bed of the frame 10 and on out to the curved end-portion 107, where it may slide by gravity down against a swinging stacking finger 108, which acts to stack the used plates in the 55 second magazine 109 in the same order they were arranged in magazine 11. The web W may be fed through the addressing machine by the operative pulling it ahead, against the slight tension, due to the weight

of the stretch of web in the rear of the 65 magazine 11, from rear to front, step by step, and gaging it to printing position by bringing a transverse fold line 110 even with a gage pin 111, which may have a rearwardly extending body 112 provided 70 with a lengthwise slot for adjustably fastening the pin by means of a screw 114 to a front portion 21^a of the plate 21. To hold the web W lightly taut at printing position and in close proximity to the plate 75 12 under it, two thin plate-members 115 and 116 may be integrally fastened to the front portion 21^a in front of and behind the ribbon 42, and extend partly over the web in engaging it. The rear plate 116 may 80 have an upwardly curved rear edge 116^a to guard against the transverse fold lines of the web catching on the plate as the web passes under the plate.

This method of feeding the web W 85 through the addressing machine permits the use of a standard addressing machine arranged with a few inexpensive additional parts, and is well adapted for use with a roller-platen-type of machine, since any 90 tendency for the rearwardly rolling platen to buckle or pull top plies of the web with it, can be easily and conveniently resisted by the operative's hold on a portion of the web ahead of the platen. By transversely 95 fan-folding the web W into a pile before feeding it through the addressing machine, there is provided a distinct and convenient gaging mark for each form. It also permits the printed portion of the web to be 100 arranged flat or on edge on a work-pile W^b, so that its leading edge may be accessible for convenient feeding to a fan-fold typewriting machine as is set forth in said application. Additional information, such as 105 a memorandum of deposits, may be manifoldly typed on a set of forms as required, the forms being fed through the typewriting machine in the same order they were fed through the addressing machine. This 110 method permits the memoranda of the additional information to be typed on the several forms, and to be conveniently kept in the same alphabetical order as the printed plates 12. When the required information is typed on the forms of a set, the set 115 may be severed from the web with its several forms left connected along the end-fold lines, until the information has been checked and approved.

In Figure 7 is illustrated how adjoining forms F^a, F^b and F^c of a set in the web fan-folded latitudinally are alternately printed on opposite sides of one web. The several plies of the web W may be made from separate pieces of paper of varying thicknesses and color, and be padded on the edges at one side, as disclosed in my Patent, No. 1,400,-

572, dated December 20, 1921. In such cases, all forms may be printed on the same side of the plies.

Variations may be resorted to within the scope of the invention, and portions of the improvements may be used without others.

Having thus described my invention, I claim:

1. In a multiple-addressing machine, the combination with an addressing machine having a printing-plate magazine, a printing bed disposed forward from said magazine, and a roller-platen, of an anti-friction element including a roller mounted on said machine at the rear and near the bottom of said magazine, two anti-friction rollers mounted at the top of said magazine, one at the front and one at the rear thereof, a roller mounted on said machine at the front of said magazine a short distance above said printing bed, said rollers adjacent said magazine being laterally disposed and arranged for passing a forwardly-fed work-web over the same from a work-pack below the bottom of said magazine at the rear thereof, and along said printing bed to printing position under said roller-platen, and means for lightly pressing said work-web against said printing bed adjacent said printing position, said rollers and said means co-operating to permit the weight of said web behind said magazine to keep slightly taut the stretch of said web disposed on said printing bed to the rear of printing position.

2. In an addressing machine, the combination of a printing bed, a type-plate magazine, a platen movable toward the printing bed and movable rearwardly thereon to make type-plate impressions on a work-web fed from rear to front, anti-friction guide means for guiding said work-web from a work-pile in the rear of said magazine and adjacent said printing bed to printing position, and instrumentalities co-operating with said means for maintaining said work-web slightly taut to the rear of said printing position.

3. In a multiple addressing machine, the combination of addressing means, a rearwardly-moving roller-platen, a carbon-holder arranged to hold carbon-sheets at their rear edges interleaved with a plurality of work-plies in printing position, and means for moving said carbon-holder to bring successive portions of said carbon-sheets to printing position.

4. In a multiple addressing machine, the combination of addressing means, a rearwardly moving roller-platen, a carbon-holder arranged to hold carbon-sheets interleaved with a plurality of work-webs in printing position, and means for feeding the carbon-sheets from rear to front to

bring successive portions thereof to printing position.

5. In an addressing machine, the combination of a main frame, a printing bed, a platen, a platen-carrying mechanism arranged to move said platen downwardly to engage against a multiple-ply work-web on said printing bed and roll said platen rearwardly, a carbon-holder mounted on said frame in the rear of said printing bed, and carbon-sheets in said carbon-holder interleaved with the work-plies of said web, said web being fed through said machine from rear to front, said carbon-sheets extending forwardly from said carbon holder.

6. In an addressing machine, the combination of a printing bed, a roller-platen, a platen-carrying mechanism operable to move said platen downwardly for engaging against and rolling rearwardly on a work-web, the latter being arranged to be pulled step by step by an operative's hands from rear to front through said machine, and means controllable by the operative's foot for effecting the operation of said platen-carrying mechanism.

7. In an addressing machine, the combination of a printing bed, a platen arranged for rolling rearwardly on said printing bed in engagement with a longitudinally-fan-folded web, carbon-sheets interleaved with the folds of said web, and a carbon-holder positioned for holding said carbon-sheets interleaved with the folds of said web, so that the pull of said web resulting from action of said rolling platen will not tear said carbon-sheets loose from said carbon-holder.

8. In a multiple addressing machine, the combination of a main frame, an addressing means, a platen arranged for rolling rearwardly on said frame in engagement with a longitudinally-fan-folded web, carbon-sheets interleaved with the folds of said web, and a carbon-holder for holding said carbon-sheets mounted on said frame to the rear of the rearmost travel of said platen.

9. In a multiple addressing machine, the combination of a main frame, an addressing means, and a platen arranged for rolling rearwardly on said frame in engagement with a longitudinally-fan-folded web manually fed from rear to front, a carbon-holder being adjustably mounted on said frame for normally moving carbon-sheets, so that the new portions of said carbon-sheets may be moved to printing position in the same direction as the web moves through said machine.

10. In an addressing machine, the combination of a main frame, means for printing a work-web manually fed from rear to front through said machine, carbon-sheets interleaved with the plies of said web, a carbon-holder for said carbon-sheets, means

for adjustably mounting said carbon-holder on said frame, said mounting means including an upper movable plate supporting said carbon-holder, a pair of downwardly-projecting pins on said plate, a base-plate fastened to said frame in the rear of the printing position of said machine, and arranged with a plurality of pairs of holes arranged for receiving said projecting pins, and flexible fingers pivoted on said base-plate and arranged to be swung over and to press down on said movable plate.

11. In an addressing machine, the combination with a printing bed, means for printing with ink the lowest ply of a multiple-ply work-web manually fed from rear to front through said machine to printing position, and means for manifolding the data on said lowest ply upon the remaining plies of said web, of instrumentalities arranged for pressing said work-web lightly and continuously against said printing bed adjacent said printing position, to reduce the tendency of said web to be moved by engagement with said means.

12. In an addressing machine, the combination with a main frame including a printing bed, and means for printing a work-web manually fed from rear to front through said machine, of plate-members supported on said frame and extending from one side over said web for pressing the latter lightly against said bed at printing position of said machine, and adjustable side gages for said web supported on said frame in front of the printing position of said machine, said front side gages being arranged to extend inwardly over said web a short distance, to guard against the web being inadvertently moved from under said plates or from between said gages while being fed through said machine.

13. In an addressing machine, the combination of a main frame, a printing bed, means for printing a work-web manually fed from rear to front through said machine, adjustable side gages arranged for guiding said web through said machine at right angles to the printing line thereof, and flat plates extending partly across said web, and arranged for holding the web constantly in close proximity to said printing bed.

14. In a multiple-addressing machine having a main frame, the combination with a motor-driven addressing means, of foot-operable means actuatable by an operative at the delivery end of said machine for controlling the operation of said motor-driven means, a printing bed, means including a lateral guide-member at each side of said frame adjacent the ends of said main frame for guiding a work-web pulled ahead lengthwise of said printing bed to printing position thereon by said operative, and a device for gaging said work-web to printing posi-

tion, said device being positioned adjacent said delivery end to be conveniently viewed by said operative.

15. In a multiple-addressing machine, the combination of an addressing means arranged for moving a roller-platen rearwardly on a work-web, which is fed forwardly through said machine, a carbon-holder in the rear of printing position arranged to hold carbon-sheets interleaved with a plurality of work-plies of said web at printing position, and means for feeding the carbon-holder, step by step, to dispose successively used portions of the carbon-sheets in front of printing position, so that said work-plies creeping under action of said moving roller will not engage with and tend to rupture the weakened used portions of said carbon-sheets.

16. In a multiple addressing machine, the combination of a plate-holding means for holding type-plates in effective position, a platen arranged for rolling rearwardly on said type-plates at printing position, a ribbon-guide between the platen and the effective position of the plates for marking the first ply of a work-web, and carbon-sheets interleaved between other web-plies and located between the platen and the effective position of the plates for marking a superposed work-ply at the same operation.

17. In a multiple addressing machine, the combination of a rearwardly-rolling platen, type-plate-moving means arranged for co-operating with said platen to move new type-plates to printing position, a plurality of type-plates, and a plurality of manifolding means between the platen and the printing position of the type-plates for co-operation with the type-plates to manifold successive sections of superposed work-plies fed through the machine in the opposite direction to the movement of said platen.

18. In an addressing machine, the combination of a main frame, a motor-driven printing means, a foot-control mechanism for said printing means, and instrumentalities for laterally guiding a work-web pulled through said machine by an operative at the delivery end of said machine, said instrumentalities including two sets of side guide-members, the first being positioned at the rear of the printing position of said machine and the second at the front of the printing position, a gage disposed in front of the printing position for stopping said work-web thereat, said second set of side members being positioned a short distance in advance of said gage, whereby said operative may conveniently manipulate said work-web and use said gage while keeping his foot on said mechanism.

19. In an addressing machine, the combination of a printing bed, a roller-platen arranged to be swung downwardly against

- said bed and moving rearwardly thereon, and means including a plate disposed on each side of the printing position and extending across a work-web for continuously holding the latter in close proximity to said bed at the printing position as it is fed forwardly, the rear plate having an upturned portion to provide an entrance throat for said work-web.
- 10 20. In a multiple-addressing machine, the combination with an addressing machine, a printing-plate magazine positioned adjacent the rear of said machine, a printing bed forward of said magazine and a roller-platen movable rearwardly on said bed, of anti-friction means for guiding a forwardly-moved hand-fed work-web from a work-pack in the rear of said machine over said magazine, downwardly to said bed, and 15 therealong to printing position, and instrumentalities for continuously pressing said work-web lightly against said printing bed on each side of the printing position of said machine, said means and said instrumentalities co-operating to keep said web smooth and taut when it is stopped to be printed.
- 20 25. In an addressing machine, the combination with a horizontal printing bed, a printing plate disposed in printing position on said bed, a roller-platen movable across said plate, and means for feeding an inked ribbon across said printing plate to print data on a work-web fed over said printing position step by step, of means for pressing said work-web lightly and continuously down against said printing bed, and instrumentalities for holding said work-web out of contact with said inked ribbon while said web is being fed forwardly, whereby the web may be kept free from smudging by said ribbon.
22. In an addressing machine, the combination with a printing bed over which may be fed from rear to front a cross-folded multiple-ply work-web, each of the plies of said web being previously printed on its lower side with a series of forms, the folds of said web having a definite relation to said forms, and the plies of said web being fed through said machine with their unprinted sides up, of a gaging device positioned forwardly of the printing position and arranged for co-operation with said folds to gage said forms to printing position on said printing bed.

JESSE A. B. SMITH.
